INVENTOR
Swan E. Nord
BY J. H. Rivers
ATTORNEY

UNITED STATES PATENT OFFICE.

SWAN E. NORD, OF SEATTLE, WASHINGTON.

FUNNEL FOR LIQUIDS.

Application filed July 27, 1926. Serial No. 125,200.

In making wholesale deliveries of lubricating oil from motor trucks, for instance, it is customary to include as a part of the equipment one or more funnels for pouring the oil. To expedite delivery of the oil it is desirable, obviously, that the funnel used should have a relatively large capacity. A disadvantage arising from such use of the ordinary funnel is that considerable oil adheres thereto, and when the funnel is returned to the truck—necessarily in an inverted position so that it will be carried in the most expedient manner—said oil leaks into the truck.

One object of my invention is, to provide in a funnel an inwardly disposed flange-like section continuous with the edge of its intake portion which affords a receptacle for oil which may run down from the interior of the funnel, and thus prevent its leakage from the funnel when the same is inverted.

Another object is, to provide a funnel especially designed for pouring oil in large quantities, having interiorly a specially constructed bottom and side walls which facilitate the flowing of the oil therethrough and the deposition of the residue in said receptacle, at the same time prevent waste by minimizing the amount of oil adhering to the funnel.

Other objects may appear as the description of the invention progresses.

In the accompanying drawing—

Figure 1 is a perspective of the preferred form of the device, complete;

Fig. 2, a longitudinal section, drawn centrally thereof; and

Fig. 3, a cross section, drawn on the line 3—3, of Fig. 2.

The device, in its preferred form, comprises a rectangular metallic box, generally designated as 1, having a doubly constructed bottom portion and side walls. Said construction includes a sheet of metal bent to form a V shaped bottom portion 2 and vertically extending side walls 3, each of the walls being bent to provide an inwardly disposed flange 4, the inner edge of which is bent downwardly, as at 5, forming a channel 6. The said portion and walls are secured within the box by soldering, or in any other suitable manner, the walls lying contiguous with the side walls of said box, as shown in Fig. 3, and the terminals of the

portion secured to the ends of the box, as indicated at 7, Fig. 1. The bottom portion 2 is disposed within the box at a downward angle, as illustrated in Fig. 2, to facilitate the flow of a liquid within the funnel to the outlet pipe 8, which is secured to said portion in any appropriate way, and, as is evident, communicates therewith.

Each upper end of the box is likewise bent to form an inwardly disposed flange and a channel, and as the same are identical in form with those heretofore described relative to the vertically extending side walls, each is given the same numerical designation, as will appear in Fig. 2. Said parts, in connection with the adjacent walls and secured together as shown in Fig. 1, provide a strengthening rim for the box and interiorly a channel-like receptacle to receive the residue of the oil, when the device is inverted, and as will be hereinafter more particularly described.

For convenience in carrying or manipulating the device, a handle 9 is provided, and which, in the present embodiment of the invention, is formed from a length of strap iron, secured to the bottom of the box and adjacent one end, by the screws 10, as illustrated.

In utilizing the funnel, in pouring oil for instance, the flat exterior bottom portion permits it to rest securely on the container into which the oil is to be poured, and the interior bottom portion, sloping from each side and toward the outlet pipe is of a form which obviously hastens the flow of the liquid into the container. Some oil, owing to its viscosity, will necessarily adhere to the interior of the funnel, but, as is evident, the double bottom eliminates a number of right angular sections in which the oil would be retained or from which the same would move slowly. The device thus permits a quicker distribution, and the recipient is assured of a more complete measure.

When the funnel is returned to the truck, for instance, it is placed in an inverted position, when any oil remaining in the outlet pipe, the V shaped bottom portion or the side walls, will gradually run into and then be retained by the channel-like receptacle extending throughout the rim, and thereby prevented from leaking into the truck.

The interior of the device, as shown and described, is especially designed to aid the

flow of liquid from the funnel and to cause the residue to run into said receptacle, but it is apparent that the form of the interior can be varied and like results attained.

5 A liquid, particularly so when it is of a viscous nature, has a tendency to adhere to and gradually run down a sloping or vertical surface rather than to fall in drops, and the instrumentalities shown and described have 10 been designed to take advantage of this characteristic and thus prevent said leakage through funnels and do away with the inconvenience, and, to a certain extent, the waste caused thereby.

I claim:

A funnel for viscous liquids, comprising a rectangular box open at the top and provided with a horizontal bottom, an outlet pipe extending through the bottom of the box, and a strengthening rim extending continuously with the edge section of the top and in right angular relation thereto, having an interior channel communicating with the sides and ends of the box, adapted to catch and retain deposits of liquid from the box when the funnel is in an inverted position.
